CLAIM

I claim the ornamental design for a vapor product packaging, as shown and described.

DESCRIPTION

FIG. 1 is a top, front, right perspective view of the claimed design;

FIG. 2 is a right side elevation view thereof;

FIG. 3 is a front elevation view thereof;

FIG. 4 is a rear elevation view thereof;

FIG. 5 is a top plan view thereof;

FIG. 6 is a bottom plan view thereof; and,

FIG. 7 is a left side elevation view thereof.

The dash-dash broken lines shown in the drawings illustrate portions of the vapor product packaging that form no part of the claimed design. The dash-dot-dash broken lines represent a boundary of the claim and form no part of the claimed invention.
